THREAD-CUTTING DIE

Maurice L. Burt, Stoughton, Mass.

Application July 23, 1942, Serial No. 452,110

8 Claims. (Cl. 10—116)

This invention relates to improvements in thread cutting tools and adjustable hollow mill cutters. More especially it has to do with a tool for cutting threads very accurately and is particularly concerned with the provision of separate cutters which may be collectively adjusted for cutting and removed from the tool and sharpened individually.

Usually with tools made for cutting accurate threads on stock of rather small diameter, where the threads made must be of uniform pitch dimension and very accurately cut, the cutters are formed as integral sections of a block. With such construction it is very difficult to sharpen the cutter sections when they become dull. It is sometimes impossible to get a stone or wheel between them and even when possible it is still more difficult to sharpen all the sections alike so that each will bear its proportionate part of the cutting operation.

The primary object of my improvements is to provide separate and distinct cutters which may be easily removed from the tool and individually sharpened. This not only makes the task of sharpening much easier and quicker to perform but enables all the cutters to be sharpened alike. Another object of the improvements is to provide simple means for accurately positioning and holding the separate cutters in place on the tool and in providing for their close adjustments to insure that the desired threads may be produced with the requisite accuracy.

The best mode in which I have contemplated applying the principles of my improvements is shown in the accompanying drawing but these are to be deemed illustrative because it is intended that the patent shall cover by suitable expression in the appended claims whatever features of patentable novelty exist in the invention disclosed.

In the drawing:

Figure 1 is an exploded view of the several parts of my improved tool in separated relations;

Figure 2 is a longitudinal section, taken as on line 2—2 of Figure 3, of the assembled tool;

Figure 3 is a section taken as on line 3—3 of Figure 2; and

Figure 4 is a perspective of one of the cutters.

Referring to the drawing, and particularly to Fig. 1, the tool comprises a body 10, a pilot bushing 12, positioning pins 14, a series of separate individual cutters 16, a locking nut 18, and an adjusting nut 20.

The body has a suitable shank 10a, either of a releasing or non-releasing type, the latter being

shown in the drawing. Near one end the body has an enlarged cylindrical section 10b which is externally threaded, and beyond these threads there is a cylindrical surface 10c. At its cutter-holding end the body is accurately faced at 10d perpendicularly to its axis. A carefully formed hole 10e in the face of the body receives the shank 12a of the pilot bushing which has a circularly flanged head 12b whose external cylindrical surface 12c determines primarily the diametrical dimensions of the threads to be cut. Pilot bushings having shanks of common size but heads of different diameters can be inserted in the body to enable the back diameter of a set of cutters to be very slightly increased and thereby prevent the cutting of any tapered portions of a thread. Secured in the face end of the body are two or more positioning pins 14 which serve to space the cutters 16 circumferentially. An axial hole is provided through the shanks and bushing to allow cutting oil to be forced to the cutting edges of the cutters.

There may be two or more cutters, four are shown, each of which is made identical with the others. Each cutter has a shank 16a which is a portion of a cylindrical wall having at its base or body end an outstanding beveled surface 16b. As seen best in Fig. 3, the body end of the cutter has sides 16c cut on radial planes from the tool axis and normally these sides rest against the positioning pins 14. This is not essential, however, and indeed if a larger pilot bushing is used, thus positioning the cutters slightly farther away from the tool axis, the radial sides of the cutters can not be in contact with two pins at the same time. In such a case, the cutters are preferably placed one against each pin so that all the cutters may be evenly spaced around the tool. At its cutting end the cutter body extends inwardly to provide a round beveled external surface 16d and to bring the cutting teeth 16e well in toward the tool axis. The teeth are very accurately formed with the usual relief toward one side.

The cutters are secured to the body by the nut 18 which at one end has internal threads which screw onto the external threads of the enlarged cylindrical section 10b of the tool body. Although not shown in the drawing, it is to be understood that a lock nut may also be screwed onto these same external threads to lock the cutter holding nut 18 in place. The other end of this latter nut has external threads 18a to receive the adjusting nut 20. Internally the cutter holding nut has a cylindrical surface 18b somewhat greater in diameter than is the cylindrical

surface 10c of the body. Beyond, in direction toward the cutting end of the tool the cutter holding nut has a beveled surface 18c which engages the corresponding beveled surfaces 16b on the shank ends of the several cutters. As the nut 18 is tightened, the engagement of these beveled surfaces seats the cutters against the cylindrical surface 12c of the head of the pilot bushing and also against the face 10d of the body. Thus the cutters are firmly and accurately secured in position.

The adjusting nut 20 has internal threads which screw onto the external threads 18a of the cutter holding nut and has a cylindrical skirt 20a terminating in a circular flange 20b which extends inward. This flange has a beveled inner edge or surface 20c which corresponds to the external beveled surfaces 16d on the cutting end of the cutters. Accordingly, when the adjusting nut is tightened to bring its beveled surface against the cutters the latter are reinforced against any tendency to spring outward. And by tightening the adjusting nut still further, the cutting ends of the cutters may be sprung inwardly slightly to obtain an exceedingly fine adjustment.

I claim:

1. A thread cutting die comprising a cylindrical body having external threads, a flat face at one end perpendicular to the axis of the body and an axial hole; a pilot bushing having a shank fitting within said axial hole and a flanged cylindrical head overlying a portion of said flat face; positioning pins mounted in said body and outstanding from said flat face outside the bushing head; a series of cutters each having a base portion with a flat end surface, a flat radial surface, an internal cylindrical surface and an external beveled surface and having a forwardly extended cutting portion with internal cutting teeth and an external beveled surface; a clamping nut having internal threads to engage the external threads on said cylindrical body, an internal beveled surface to engage the beveled surface on the base portion of each cutter, and having external threads; and an adjusting nut having internal threads to engage the external threads on said clamping nut and having an inwardly disposed flange with a beveled surface to engage the external beveled surface on the cutting portion of each cutter; the said clamping nut when tightened holding the base of the cutter against the flat face of the body, against a positioning pin, and against the flanged head of the bushing; and the said adjusting nut reinforcing the cutting ends of the cutter and holding them in-adjusted position.

2. A thread cutting die comprising a body having external threads therearound, a flat faced end, and an axial hole; a pilot bushing in said hole having a cylindrical head overlying a portion of said flat faced end; a series of cutters each having a flat faced end, an internal cylindrical surface, and an external beveled surface; a clamping nut threadable on the external threads of said body and having an internal beveled surface engaging the external beveled surface of each cutter, whereby upon the nut being tightened on said body the flat faced ends of the cutters are seated against the flat faced end of the body and the internal cylindrical surfaces of the cutters are seated against the cylindrical head of the bushing.

3. A thread cutting die comprising a body hav-

ing a flat faced end and an axial hole; a pilot bushing in said hole having a head overlying a portion of said flat faced end; a series of cutters each having a flat end face, an internal surface, and an external beveled surface and a clamping element adapted to be secured to said body having an internal beveled surface engaging the beveled surface of each cutter whereby the flat end face of the cutter is held against the flat faced end of the body and the external surface of the cutter is held against the head of said bushing.

4. A thread cutting die comprising a body having a flat faced end and an axial hole; a pilot bushing in said hole having a head overlying a portion of said flat faced end; a series of cutters each having a flat end face, an internal surface, and spaced apart external beveled surfaces; a clamping element adapted to be secured to said body having an internal beveled surface engaging one of the beveled surfaces of each cutter whereby the flat end face of the cutter is held against the flat faced end of the body and the internal surface of the cutter is held against the head of said bushing; and an adjusting element adapted to be secured to said clamping element and engaging the other beveled surface of each cutter whereby all of the cutters may be adjusted simultaneously.

5. A thread cutting die comprising a body; a pilot bushing associated with said body; a series of cutters each having spaced apart external beveled surfaces; a clamping element adapted to be secured to said body having an internal beveled surface engaging one of the beveled surfaces of each cutter whereby the cutters are clamped to the body and the said bushing; and an adjusting element adapted to be secured to said clamping element having an internal beveled surface engaging the other beveled surface of each cutter whereby the cutters may be adjusted simultaneously.

6. A thread cutting die comprising a cylindrical body having a flat face perpendicular to its axis; a pilot bushing associated with said body having a cylindrical edge outstanding from said flat face; positioning pins outstanding from said flat face outside the bushing edge; a series of cutters, each having a flat end surface, a flat radial surface, an internal cylindrical surface and an external beveled surface; and a clamping nut adapted to be tightened on said body having an internal beveled surface to engage the beveled surface on each cutter; the said clamping nut when tightened holding the flat end surfaces of the cutters against the flat face of the body, a radial surface of each cutter against a positioning pin, and the internal cylindrical surfaces of the cutters against the cylindrical edge of the bushing.

7. A thread cutting die comprising a body having a flat faced end; a central hub having an external cylindrical surface outstanding from said flat faced end; a series of cutters each having a flat faced flanged end, an internal cylindrically curved surface and an external cylindrically curved surface terminating in a beveled portion at its inner flanged end; a clamping element associated with said body and having an internal beveled annular shoulder engaging the external beveled surface of each cutter, whereby the flat faced ends of the cutters are clamped against the flat faced end of the body and the internal curved surfaces of the cutters are clamped against the external cylindrical surface

outstanding from said flat faced end of the body.

8. A thread cutting die comprising a body having a flat faced end; a pilot bushing having a head overlying a portion of said end; a series of cutters each having a flat faced flanged end, an internal cylindrically curved surface, and an external cylindrically curved surface terminating in a beveled portion at its inner flanged end; a

clamping element associated with said body and having an internal beveled annular shoulder engaging the external beveled surface of each cutter, whereby the flat faced ends of the cutters are clamped against the flat faced end of the body and the internal curved surfaces of the cutters are clamped against the head of the bushing.
